UNITED STATES PATENT OFFICE.

EDWARD BELLMAN, OF EVANSVILLE, WISCONSIN.

MANUALLY-PROPELLED LIFE-SAVING DEVICE AND ATTACHMENT FOR BOATS.

1,401,233.

Specification of Letters Patent. Patented Dec. 27, 1921.

Application filed April 26, 1921. Serial No. 464,574.

To all whom it may concern:

Be it known that I, EDWARD BELLMAN, a citizen of the United States, and resident of Evansville, in the county of Rock and State 5 of Wisconsin, have invented certain new and useful Improvements in Manually-Propelled Life-Saving Devices and Attachments for Boats; and I do hereby declare that the following is a full, clear, and exact 10 description thereof.

This invention relates to a new and improved manually propelled life saving device and attachment for boats, whereby the occupant of the boat may propel and steer 15 the same while in either sitting or lying position.

One object of my invention is to construct a boat of this kind which will be in the nature of a novelty to be used for various 20 forms of popular aquatic sports at summer resorts.

A further object of the invention is to provide a propelling device which may be attached to any row boat, canoe, or, in fact, 25 to any device to be propelled over the water and which may be operated by a person sitting or lying therein.

Another object of the invention is to construct a life saving device which will be 30 practically unsinkable and will thoroughly protect the occupant from the waves no matter how rough they may be.

Other and more specific objects will be apparent from the following description 35 taken in connection with the accompanying drawings, in which:

Figure 1 is a longitudinal vertical section as indicated by the line 1—1 of Fig. 3.

Fig. 2 is a plan view of the boat without 40 the cover, as indicated by line 2—2 of Fig. 1, and

Fig. 3 is a cross sectional view thereof.

The boat comprises the lower portion 5 which is made of a shape and size to conveniently accommodate a single person lying 45 prone therein. It will be understood, however, that in fair weather with the cover removed the occupant may sit up in the same position as in an ordinary boat.

This boat is provided with suitable air 50 tight compartments 6 to render the same buoyant. At the rear end of the portion 5, I provide a propeller 7 of the usual type carried by the shaft 8, and extending with- 55 in reach of the operator's feet where pedals 9 are provided which are operatively con-

nected to the shaft 8 by a beveled gear- 60 ing 10.

The shaft 8 is carried within a sleeve 11 which is adjustable longitudinally within 65 the bracket 12 mounted inside the boat, and the sleeve is secured in its adjusted position by means of a set screw 13. The purpose of this adjustment is to enable the pedals to be adjusted to accommodate persons of differ- 70 ent height.

A rudder 14 is carried on the shaft 15 which is rotatable in the bearings 16 ex- 75 tends from the rear end of the boat. Arms 17 are provided for swinging the rudder to steer the boat, and the extremities of these arms are secured to a flexible cable 18, which passes over the sheaves 19 to a point within reach of the operator's hands.

Lateral planes 20 are also provided which 80 are mounted on the shaft 21 which may be mounted on the shaft 21 which may be rocked by means of the handle 22. These planes are for the purpose of guiding the boat up and down.

My boat may be operated on the surface 85 of the water without a cover, but for the purpose of converting it when desired for use in rough water, I provide a cover 23 which is also provided with air tight com- 90 partments 24. This cover is adapted to fit tightly and may be securely attached by the person within the boat, by means of the bolts 26, which are secured in the brackets 25 attached to the sides of the boat and its cover.

I also provide an opening 27 through 95 which a mirror 28 mounted on top of the cover, is visible to a person lying within the boat. This mirror 28 enables the person lying within the boat to observe his surroundings and see any object which he may be approaching.

It will readily be understood from the foregoing description, that my invention may be readily adapted to many different 100 kinds of aquatic sports. For example, it may be used without a cover to ride along the surface of the water, and the operator clad in a bathing suit may raise or lower the planes 20 to pass over or through the 105 water. It is to be borne in mind that the boat will not sink even though filled with water since the air tight compartments render it buoyant.

When a person wishes to use it as a life 110 boat he gets inside and secures the cover thereon by means of the bolts 26. He may

then propel himself in the boat over the surface of the water, guiding himself by means of the rudder 14 and using the planes 20 to keep the boat above the surface. He 5 can also observe the direction in which he is going and any objects which he may be approaching by means of the mirror 28. He will be absolutely safe from drowning, no matter how violent the waves may be.

10 While I have described one form in which my invention may be embodied, it will be understood that many modifications may be made therein, without departing from the spirit of the invention, as defined by the 15 appended claims.

I claim:

1. A boat of a size and shape to conveniently accommodate a man lying prone therein, a revoluble propeller mounted 20 therein, pedals operatively connected to said propeller to revolve the same, and means

for adjusting the propeller and pedals longitudinally to accommodate persons of different height.

2. A boat provided with a revoluble propeller, pedals operatively connected to said propeller to revolve the same, a cover for said boat adapted to form therewith, a closed compartment within which a person may lie with his feet within reach of said 25 pedals, means by which the cover may be securely attached by a person within said compartment, a window in said cover and a mirror on top of said cover and visible through said window to a person lying in 30 the boat.

In testimony that I claim the foregoing I have hereunto set my hand at Evansville, in the county of Rock and State of Wisconsin.

EDWARD BELLMAN.
